UNITED STATES PATENT OFFICE.

EDMUND R. WEEK AND EDMUND R. WEEK, JR., OF SPOKANE, WASHINGTON.

METHOD OF HYDRAULIC MINING AND THE LIKE.

1,261,198.

Specification of Letters Patent. Patented Apr. 2, 1918.

Application filed February 7, 1916. Serial No. 76,628.

To all whom it may concern:

Be it known that we, EDMUND R. WEEK and EDMUND R. WEEK, Jr., citizens of the United States, residing at Spokane, State 5 of Washington, in the county of Spokane, have invented new and useful Improvements in Methods of Hydraulic Mining and the like, of which the following is a specification.

This invention relates to hydraulic placer 10 mining or to the hydraulic moving of earth, such as bodies of gravel, etc.; and, among other objects of this invention, it is an object to provide a method in which a minimum amount of water is required and in which 15 the debris is deposited dry and is not to be deposited in a stream, or water course, in such manner as to be washed into a stream. In this last regard the invention has for one of its objects the provision of a method of 20 hydraulic mining, or mining of material, which will comply with the statutes prohibiting or restricting the deposit of placer debris in flowing streams.

Other objects of this invention are made to 25 appear in the following specification, wherein we explain preferred forms of our invention, and preferred forms of our apparatus or machinery for carrying our invention into effect. In the accompanying drawings we 30 have illustrated, for the purpose of this specification, the application of our method to two different situations, although it will be understood that our method may be applied to other situations.

35 In the accompanying drawings Figure 1 is a diagrammatic plan showing one arrangement for carrying out our invention, Fig. 2 is a vertical section showing the same, and Fig. 3 is a diagrammatic plan showing our 40 invention applied to another situation.

Referring first to Figs. 1 and 2 of the drawings, we have shown a situation where there exists a relatively steep sloping bed rock surface 10 with the mineral bearing 45 gravel 11 on the surface. It will be understood that in hydraulic mining it is always preferred to wash down the gravel completely and cleanly to the bed rock surface; and, in the situation illustrated, we arrange 50 the hydraulic machinery on the sloping surface below the bank 12, moving the machinery up the sloping strata from time to time as the gravel is washed away and the bank 12 recedes.

55 We provide a nozzle 20 of any suitable type mounted upon a suitable foundation 21

in such position that the stream of water 22 may be played effectively upon the bank. Water under pressure is supplied to the nozzle through a pipe 23 from a high pressure 60 pump 24, which pump may be multiple stage centrifugal pump operated from any suitable source of power. Any suitable means may be employed for forcing the water. The gravel washed down with the 65 water flows downwardly on the slope 10 and is directed by any suitable means, as by walls 25, into the sluice box or flume 26. This sluice box is equipped with any of the usual means for saving the particles of mineral which settle out of the flowing stream of water and material; and the sluice box may be of any desired length. At the lower end of the sluice box, or flume, we provide any suitable means for separating out the 75 gravel, as by providing a grizzly or screen 30 through which the water may flow. The water may then flow directly from the grizzly or other separating means to the sump 31; or any further means as at 26^a may be interposed between the sluice box and the sump to further separate out any solid particles still held in suspension by the water.

The sump reservoir or hole is formed by stacking the debris, in this particular instance, a semi-circular mound as shown at 32; and this may be accomplished by any suitable carrier or conveyer or stacker. In the drawings we have indicated a tower or pole 40 having a swinging boom 41 upon 80 which a belt conveyer 42 may be carried, the conveyer reaching down to a point where the debris is separated by the grizzly. This conveyer is kept in continuous operation with its end suspended over the ridge of the 90 mound 32; and the debris is distributed in hollow circular formation or substantially in a semi-circle so as to form a semi-circular embankment above which the sump 31 may be stored. Or the debris may be carried a 100 farther distance by other conveyers, as indicated at 42^a. As the bank 32 increases in size its upper slope will move up the strata 10; and the same is of course true whenever the machinery is moved bodily up the slope, 105 a new bank being formed higher up, or a continuation of the old bank being formed on its upper face. The result of such operation, continuously carried on is that the original gravel bank 11 is removed and re-deposited a short distance down the slope in 110 the bank 32. The water flows into the pocket

or hole above the bank 32 and the pump 24 draws its supply of water through a suitable pipe or hose or other induction means 45. The amount of water used is such as to allow it to stand sufficient time in the sump to drop the smaller particles of silt, so that the water picked up by the pump 24 is comparatively clear. The only loss of water is by evaporation and leakage and seepage; but this loss is very small as compared with the total amount of water used at the nozzle; so that, once an original supply of water being had, very little additional water is thereafter required. The debris is deposited dry, rather than in suspension in the water as has heretofore been the practice; and, accordingly, the debris will not be carried into an adjacent water course. The silt separated from the water may be deposited 20 on the upper face of the debris bank to make it water tight.

Figs. 1 and 2 show the debris piled as it will be on more or less slope, to form a pocket for water storage. Where the natural topography allows, the debris may be deposited as a bank or dam across a canyon, cut, gulch or other depression and the water stored above the bank so formed. For instance the working may be along a narrow strip of gravel or along the edge of a ravine or draw, and then the debris may be deposited along in the cut or in the ravine or draw as the working progresses along it. It will be understood that the nature of the debris deposit will depend upon the natural ground features at the working.

In Fig. 3 we have illustrated the application of our method to a different situation where the gravel bank does not stand in such a manner as to allow the practice illustrated in Figs. 1 and 2. The gravel bank or gravel deposit 11^a may be situated at an elevation above a ravine or the like 51. In this case a tunnel 52 may be driven through the ridge 50 and the sluice box 26^a may be continued on through the tunnel 52 as illustrated at 26^b. Where the tunnel emerges into the ravine, or other depression, the water and solid matter may be separated at 30^a on a grizzly or the like and the debris thrown out into the ravine, being then handled in any suitable manner. For instance, the debris may be carried or conveyed down a short distance and deposited in the form of a dry bank or deposit. The surface water which runs down such a ravine in wet weather may be diverted in any suitable manner. The water may then be carried through further separating devices, as indicated at 26^c, where the mineral may be further separated from the water after which the water may run into a box 53. From the box 53 a pump 54 lifts the water to a reservoir 55; and from the reservoir 55 a high pressure pump 24^a forces 60 the water through the pipe line 23^a to the

nozzle 20^a, whence it is delivered into the stream 22^a against the bank 12^a. The settling from the water in the reservoir may be further treated for extraction of metal, if desired.

We have described our invention in connection with placer mining; but it will be understood that our method may be applied to any situation where it is desired to move a body of earthy material which can be moved by hydraulic means. For instance, banks of gravel, shale, sand or the like may be moved; and with our method a minimum quantity of water is required and the earth is deposited dry.

In situations where there is a plentiful supply of water easily had the water is not necessarily impounded and returned to the nozzle but may be allowed to escape; but in any case the debris is separated from the water and piled in dry state, the water flowing away after clarification. The essential feature in this case is the separation of water and debris and disposition of the debris independently of the water and in dry state. An outstanding feature of this invention is the separation of the water and the debris so that the debris may be handled dry and so that the water may be again pumped to the hydraulic nozzle; with the result that the water is carried through a closed cycle and is retained (with the exception of a small amount of leakage and evaporation) at all times with the system of operations rather than being discharged from the system at any time as is now commonly the case.

The advantages of such a system of operation are many, including the material and very important reduction in the amount of water supply required, making our method applicable to placer work in the desert or other place where water is very scarce, and in any case reducing the cost of obtaining water; increasing the percentage of mineral saved, for the reason that the water which, in ordinary practice, carries away a large percentage of the fine minerals in suspension, is retained entirely within our system of operation; and entire obviation of the necessity of depositing it in such a manner that it will be washed into such a water course or stream. When we say that the debris is deposited dry, it will be understood that we mean that it is not deposited in suspension in a fluid or deposited with a sufficient amount of fluid to cause it to wash into the nearest water course, as is generally the case. The debris is damp when deposited; and this dampness assists it to consolidate to form a solid mass of deposit which will not readily move from place to place.

Having described a preferred form of our invention, we claim:

1. The herein described method, embody-

ing washing down a body of earth by directing water against it, flowing the water and debris in suspension away from the original body, separating the coarser parts of the debris from the water, piling the separated debris in dry state to form a storage pit for the water, discharging the water with the fine suspended debris against the pit walls formed by the separated debris so that the fine matter in suspension settles against the pit walls and makes them water-tight, and then taking water from the pit to be again directed against the body of earth.

2. Apparatus for the herein described process, embodying means to direct a jet of water against a body of earth, a separator adapted to separate the debris from the water, means for directing the water and

debris from the body of earth to the separator, means embodying a swinging conveyer for piling the debris in such formation as to form a pit for the water, means for directing the water and unseparated fine material from the separator onto the banks of the pit thus formed so that the fine material may settle on the bank and make it water-tight, and means to take water from the pit and deliver it to the water jet.

In witness that we claim the foregoing we have hereunto subscribed our names this 28th day of January 1916.
